E. E. ALLEN.

DOOR OPENER.

APPLICATION FILED JAN. 20, 1920.

1,337,384.

Patented Apr. 20, 1920.

By Arthur H. Sturges.
Attorney

UNITED STATES PATENT OFFICE.

EARL E. ALLEN, OF COUNCIL BLUFFS, IOWA.

DOOR-OPENER.

1,337,384.

Specification of Letters Patent. Patented Apr. 20, 1920.

Application filed January 20, 1920. Serial No. 352,730.

To all whom it may concern:

Be it known that I, EARL E. ALLEN, a citizen of the United States, residing at Council Bluffs, in the county of Pottawattamie and State of Iowa, have invented certain new and useful Improvements in Door-Openers, of which the following is a specification.

The present invention relates to improvements in door openers or door pulls and the invention will be found more particularly useful in connection with screen doors, although of course it is understood that the invention is not limited to this application alone.

It is an object of the present invention to provide a device on a swinging screen or other door that may be engaged by the foot to pull the door open, when the hands are otherwise occupied as for instance in carrying bundles. The invention obviates the necessity for putting down the bundles in order to free the hands.

Another object of the invention is to provide a device for the above described purpose which will be capable of reversal to fit doors that open either from the left toward the right or from the right toward the left, whereby it will be unnecessary to manufacture the devices in right and left shapes and to inspect them before application to any particular door.

A further object of the present invention resides in providing an improved door opener which will be simple in construction and adjustment and will be cheap in manufacture.

The above, and various other objects and advantages of this invention will in part be described in, and in part be understood from, the following detailed description of the present preferred embodiment, the same being illustrated in the accompanying drawings, wherein:

Figure 1 is a fragmentary elevational view of a door which opens from the left toward the right, and which is shown equipped with an improved door opener constructed in accordance with the present invention.

Fig. 2 is a similar view showing a door that swings in the opposite direction also equipped with one of the improved devices.

Fig. 3 is a side elevation of a device constructed according to the invention.

Fig. 4 is an edge view thereof.

Fig. 5 is a view similar to Fig. 3 but showing the parts reversed for application to a door that swings from the left toward the right.

Fig. 6 is a side elevation of the plate and its flange.

Fig. 7 is an end view of the device and,

Fig. 8 is a plan view of the foot rod and its shank.

Referring more particularly to the drawings which show only one mechanical embodiment of the invention, 10 designates a plate advantageously, although not necessarily, of general triangular form having its apex cut away, and 11 represents a flange 70 projecting at an angle from the plate 10, preferably an obtuse angle of substantially the degree indicated in Fig. 4. The flange 11 is also of a shape approaching a triangle and is perforated with one or more holes 12, 75 through which nails, screws or other fastening means may be passed to secure the flange 11 against the outer surface of a door.

As shown more particularly in Fig. 6 the plate 10 is also provided with perforations, 80 which are three in number, the same being arranged in substantially triangular formation, the apex perforation 13 being located in the vicinity of the center of the plate 10, while the perforations 14 and 15 are placed 85 near the reduced free end of the plate 10 and are arranged in vertical alinement, one spaced above the other. The perforation 14 lies in a horizontal plane above that of the apex perforation 13, and the perforation 15 90 lies in a horizontal plane below said apex perforation 13.

The apex perforation 13 is adapted to receive a bolt, or other fastening means, 16, which also passes through a shank 17 near 95 one end thereof and forms a center about which the shank 17 may rotate through a limited degree. The shank 17 also carries a bolt, or other fastening means 18 which may engage through the perforations 14 in the 100 plate 10, as shown in Fig. 5; or, after the shank 17 is rotated about the bolt 16, the other bolt 18 may enter the perforation 15 of the plate 10 as shown in Fig. 3. Figs. 3 and 5 show the parts reversed.

Fig. 1 shows a door 19 adapted to close in a frame indicated at 20 and supported to swing on hinges 21. The door 19 in this figure swings from the left toward the right. An improved device according to the pres- 110

ent invention is shown applied to this door 19, the condition of the parts being that shown in Fig. 5, in which the bolt 18 engages through the perforation 14.

5 As shown in Fig. 2 a door 22 is mounted in the frame 23 on hinges 24 that allow of the door opening from the right toward the left. In this figure is also shown a device according to the present invention and with 10 the parts assembled as shown in Fig. 3, wherein the bolt 18 occupies the perforation 15 of the plate 10. The rotation of the shanks 17 about the bolt 16 and the interchangeable engagement of the bolt 18 with 15 either perforation 14 or 15 enables the device to be readily and conveniently reversed for application to doors of the type shown in the above Figs. 1 and 2.

As shown in Fig. 8 the shank 17 is preferably reinforced along opposite longitudinal edges by flanges 25 that are preferably beveled as indicated at 26. A foot piece or rod 27 is preferably formed in one piece with the shank 17 and projects at an obtuse angle therefrom; this foot piece or rod 27 being of preferably a substantially tubular form as shown in Fig. 8 for facilitating the engagement of the foot therewith.

30 In use, the foot piece 17 is held in a downwardly inclined position near the lower free edge of the door where it may be readily engaged by the foot to cause the opening of the door. The door is opened in this way easily with sufficient force to swing it to a 35 wide open position, whereby a person, for instance laden with bundles, may be enabled to pass into a house without laying down the bundles, and the door will close after such

person, as screen doors, and the like are usually provided with springs for this purpose. 40

I do not wish to be limited to size, form or proportions of the various parts and it is obvious that various changes and modifications may be made without departing from the spirit of the invention, provided such 45 changes fall within the scope of the appended claim.

What is claimed is:—

An improved door opener comprising a reversible substantially triangular plate 50 having perforations therein and adapted to be fitted against a door near the lower free end thereof, a second substantially triangular plate made in one piece with the first-named plate and extending at an obtuse angle with respect to the same, said last-named plate having three perforations therein arranged in substantially triangular formation, a bar adapted to be fitted against one side of said last-named plate, a pair of fastenings going through said bar adapted to enter the apex perforation and one of the other perforations of the group of triangular perforations whereby to reversibly hold the bar in an inclined position to the horizontal, said bar having turned up edges and 55 provided with a foot piece of tubular construction bent from the outer end of the bar at an obtuse angle with respect thereto.

60 In testimony whereof, I have affixed my 70 signature in presence of two witnesses.

EARL E. ALLEN.
